UNITED STATES PATENT OFFICE

HOWARD J. MURPHY, OF READING, MASSACHUSETTS, ASSIGNOR, BY MESNE ASSIGNMENTS, TO ALEMITE CORPORATION, OF CHICAGO, ILLINOIS, A CORPORATION OF DELAWARE

LUBRICATING APPARATUS

Application filed October 9, 1926. Serial No. 140,518.

This invention aims to provide improvements in lubricating apparatus, and more particularly to improvements in centralized lubricating systems.

5 In the drawings, which illustrate a preferred embodiment of my invention:—

Figure 1 is a general view of a central lubricating system used in connection with a motor vehicle;

10 Fig. 2 is a vertical section through the pump, being partly in elevation and showing one position of the suction and atmospheric valve mechanism.

Fig. 3 is a view of the pump similar to that shown in Fig. 2, but showing the other position of the valve mechanism;

Fig. 4 is an elevation view of the control device for the entire system;

15 Figs. 5 and 6 are cross-sectional views taken on the line 5—5 of Fig. 4, showing the sliding part of the control device in its two operating positions;

Fig. 7 is a plan section through the upper end of the pump showing the passages and 20 ports and also showing the dotted positions of the valve part; and

Fig. 8 is a section through the pump on the line 8—8 of Fig. 2.

Referring to the embodiment of my invention illustrated by the drawings, I have shown a centralized lubricating system which is particularly adapted for use in connection with lubricating the bearings of a motor vehicle chassis or of a machine.

35 In Fig. 1, I have shown the system as applied to motor vehicles. This system includes a lubricant supply reservoir, which in this instance is the crankcase 1 of the motor 2, a vacuum pump 3, a plurality of charge-determining lubricant cups 4, a plurality of conduits forming a pipe system connecting these parts and a control device 5.

The cups 4 are of substantially the same construction and operate in substantially the 45 same manner as more fully shown and described in my co-pending application Serial No. 80,244 filed January 9th, 1926. These cups may be of any other suitable construction, however.

50 When the crankcase of the engine is used

as a supply reservoir, the pipe which connects with the pump may be connected to the lubricant pump usually used in connection therewith for forcing lubricant to the bearings of the engine.

The pump 3 is mounted upon the dash 5a (Fig. 1) and includes (as shown in Figs. 2 and 3) a relatively large chamber 6 in which operates a piston 7 having connected thereto a piston 8 of relatively smaller cross-sectional area and operable in a lubricant chamber 8a. The piston 7 is driven in first one direction and then the other, in the chamber 6, by alternately creating a partial vacuum at first one side and then the other of the piston 7. At the same time, atmospheric pressure is admitted to the chamber 6 at that side of the piston 7 opposite the side at which the vacuum is created. In order to alternate the admission of suction and of atmosphere to the sides of the piston 7, I provide a quick-acting valvular mechanism which is connected through lost motion means with the piston 7 for operation thereof.

The valvular means and lost motion connection include a disk-like valve part 9, carried at one end of a lever 10, pivoted upon the pump casing as shown in Figs. 2 and 3, a rod 11 slidably connected to the piston 7 and a spring 12 connecting the rod 11 with the other end of the lever 10. The under side of the valve part 9 is hollowed so that it may communicate with at least two of a plurality of ports, as shown in Figs. 7 and 8, which connect with passages providing for exhausting the air from the chamber 6 at first one side and then the other of the piston 7. The port 13 and passage 14 provide for the admission of suction or atmosphere at one side of the piston 7, and the port 15 and passage 16 provide for the same at the opposite side of the piston, while the port 17 and passage 18 connect with the conduit 19, which connects the pump with the manifold 20 of the engine (Fig. 1). Suction in the manifold provides the means for exhausting the air from the pump at one side of piston 7.

The valve part 9 is always in communication with the port 17, but alternates in its

communication with the ports 13 and 15 as shown in Figs. 2 and 3.

During reciprocation of the pistons 7 and 8, lubricant passes from the reservoir or 5 crankcase 1 through the conduit 21 into the inlet end of the chamber 8a and is forced therefrom through the pipe system 22 connected at the outlet end of the chamber 8a. Valvular means, in the form of a threaded 10 plug 23, carrying a cup leather 24 engaging the wall of a chamber at the outlet end of the chamber 8a, is screwed into the lower end of the pump, as shown in Figs. 2 and 3. The cup leather 24 permits lubricant to pass out 15 of the lubricant chamber 8a, but prevents return of the lubricant from the pipe system 22 during the filling stroke of the piston 8.

The control device 5 may be mounted upon the instrument board 24a of the motor vehicle, as shown in Fig. 1, so that it may be within easy reach of the operator. This device 20 includes a casing made up of several bored parts secured together, a sliding valvular part 25 and adjustable detent means for holding the sliding valvular part 25 in one of its positions. The suction conduit 19 bypasses through the control device as does also a conduit 26 which connects the pipe 25 system 22 with the crankcase 1, as shown in 30 Fig. 1. Thus the sliding valvular part 25 may control the suction to the pump 3, the pressure of the lubricant in the system and return of lubricant to the crankcase 1.

The detent means includes a ball 27 adapted to engage a groove 28 in the part 25, when pressed inwardly as shown in Fig. 5, a spring 29 pressing upon the ball and a screw 30 and lock nut 31 for varying the pressure of the spring against the ball. Thus the pressure 40 required to dislodge the ball and permit movement of the sliding valvular part 25 may be varied.

Whenever it is desirable to lubricate the bearings of the vehicle, which are connected 45 by the central system, the operator need merely press inwardly on the button 32 of the control device until the ball 27 snaps into the groove 28, as shown in Fig. 5. This action moves the sliding valvular part 25 to a 50 position which aligns the groove 25a in the part 25 with the conduit 19 so that air may be exhausted from the pump chamber 6. The outer end portion 25b, of the part 25, then closes the by-pass of the conduit 26 through 55 the control device 5, so that the lubricant cannot return from the pipe system 22 to the crankcase 1.

If, when the button 32 is pressed, the engine 2 of the vehicle is not running, nothing 60 further takes place than that described in the above paragraph. If, however, the engine is running, or when it begins to run, the pump 3 will commence operating and lubricant will be forced by the piston 8 through 65 the pipe system to the cups 4 until the lubri-

cant-expelling and charge-determining means in each group cup forces lubricant therefrom to the parts to be lubricated.

Assuming that the piston 7 of the pump 3, is in the position shown in Fig. 2, the air 70 at the lower side of the piston will be drawn by suction through the passage 14 and port 13 to the valve 9, then through the port 17 and passage 18 to the conduit 19. At the same time, the port 15 is uncovered by the 75 valve and atmospheric pressure will be admitted to the upper side of the piston 7 and drive it downwardly in the chamber 6. As the piston 8 is carried by the piston 7, it will be moved downwardly in the chamber 80 8a to cover the inlet opening and prevent further entrance of lubricant and thereafter force a charge of lubricant past the washer 24 into the pipe system 22. Toward the end 85 of the stroke of the piston 7, the shoulder 33 on the part 35 carried by the piston will engage the shoulder 34 on the rod 11 and further movement of the piston will carry the rod 11 along with it. The spring 12 will then be carried downwardly until its center passes 90 beyond the center of the pivot 36 for the lever 10. Immediately thereafter the spring will throw the lever 10 and valve 9 into the position shown in Figs. 3 and 7, and the suction will then be admitted to the upper side 95 of the piston through the port 15 and passage 16. Atmospheric pressure will be admitted to the lower side of the piston 7 through the uncovered port 13 and passage 14. Thus the pistons 7 and 8 will be driven upwardly. Before the piston 7 reaches the end of its upward stroke, the wall 37 at the end of the elongated chamber 38 in the part 35 will engage the free end of the rod 11, and move the rod to snap the valve 9 from the position 100 shown in Fig. 3 back to the position shown in Fig. 2. During the beginning and mid portion of the piston stroke, there is no movement of the rod 11 because the chamber 38 is sufficiently long to permit such movement of the piston before the shoulders 33 and 34 or the wall 37 and end of the rod engage. This arrangement provides for quick action 105 of the valve 9 at each end of the stroke of the piston.

During the upward stroke of the piston 8, suction is created in the chamber 8a, but lubricant cannot return from the pipe system 22 because of the cup leather 24, and only after the piston has passed the inlet passage 110 can lubricant refill the chamber 8a.

The operation of the pump 3 continues in the manner above described until the cups 4 are filled and discharged and even then continues operation until the pressure in the pipe system 22 and the conduit 26, as far as the end of the slide valve part 25, is sufficient to move the slide valve 25 and dislodge the ball 27 from the groove 28. The sliding part 115 25 will then be moved automatically by the 120 125

lubricant to the position shown in Fig. 6, so that the suction through the conduit 19 will be cut off and the bypass through the device 5 for the lubricant will be opened. The pump 5 will then stop and the lubricant will flow from the cups 4 and the pipe system 22 through the conduit 26, back to the crankcase 1 and relieve the pressure in the system. The measuring and discharging means in the cup 10 4 may then resume their normal positions.

The system illustrated and described is simple in construction and operation. The button 32 may be pressed by the operator and thereafter every operation is automatic 15 so that the operator need not pay further attention as to when the bearings are completely lubricated. The control device is automatically operated, when lubrication is complete, to stop the pump, relieve the pressure in the system and permit all parts to return to their normal inoperative positions, so that they may be ready for immediate operation when the button is again pressed to 20 set the system for operation.

While I have shown and described a preferred embodiment of my invention, I do not wish to be limited thereby, my invention being best defined in the following claims.

Claims:

1. A central lubricating system comprising a lubricant supply reservoir, a pump, a source of operating power therefor, a plurality of lubricant cups for discharging lubricant to parts to be lubricated, conduit means connecting the supply reservoir, pump and cups and a single control device having a stem which when operated in one direction connects said source with said pump and thereby causes the pump to operate and force lubricant to said 35 cups and when operated in the opposite direction disconnects said source and pump and thereby prevents further operation of said pump and relieves the pressure of the lubricant in said conduit means.

2. A central lubricating system comprising, in combination, a supply reservoir, a suction operated pump, a plurality of lubricant cups for discharging lubricant to parts to be lubricated, a conduit connecting the pump with 40 the reservoir, a pipe system connecting the pump with the cups, a single control unit for the entire system, a conduit for bypassing lubricant in the pipe system through the control unit to the reservoir, suction means connected with said pump by a conduit also bypassing through the control unit, and means operable to prevent flow of lubricant from the pipe system back to the reservoir while at the same time opening the bypass for the 45 suction to the pump thereby to operate said pump to force lubricant to the lubricant cups.

3. A central lubricating system comprising, in combination, a supply reservoir, a suction operated pump, a plurality of lubricant 50 cups for discharging lubricant to parts to be

lubricated, a conduit connecting the pump with the reservoir, a pipe system connecting the pump with the cups, a single control unit for the entire system, a conduit for bypassing lubricant in the pipe system through the control unit to the reservoir, suction means connected with said pump by a conduit also bypassing through the control unit, and said control unit having valvular means operable to close the bypass for the lubricant back to the reservoir while at the same time opening the bypass to admit suction to the pump. 70

4. A central lubricating system comprising, in combination, a supply reservoir, a suction operated pump, a plurality of lubricant 80 cups for discharging lubricant to parts to be lubricated, a conduit connecting the pump with the reservoir, a pipe system connecting the pump with the cups, a single control unit for the entire system, a conduit for bypassing lubricant in the pipe system through the control unit to the reservoir, suction means connected with said pump by a conduit also bypassing through the control unit, said control unit comprising a casing having a single 85 slideable member located therein for opening and closing the bypass for the suction and the bypass for the lubricant.

5. A central lubricating system comprising, in combination, a supply reservoir, a suction 90 operated pump, a plurality of lubricant cups for discharging lubricant to parts to be lubricated, a conduit connecting the pump with the reservoir, a pipe system connecting the pump with the cups, a single control unit 95 for the entire system, a conduit for bypassing lubricant in the pipe system through the control unit to the reservoir, and suction means connected with said pump by a conduit also bypassing through the control unit, said control unit comprising a casing having a single 100 slideable member located therein for opening and closing the bypass for the suction and the bypass for the lubricant, said slideable member operable by hand to open the suction bypass and close the lubricant bypass and operable by lubricant under pressure to open the lubricant bypass and close the suction bypass. 105

6. In a central lubricating system having 110 a lubricant supply, a lubricant pipe system and a vacuum pump for forcing lubricant through the pipe system, a combined pump control and lubricant pressure relief device inserted in the pipe system and in a conduit 120 connecting the pump with a source of vacuum.

7. In a central lubricating system having 125 a lubricant supply, a lubricant pipe system and a vacuum pump for forcing lubricant through the pipe system, a combined pump control and lubricant pressure relief device, a lubricant conduit leading through said control device and a vacuum conduit leading through said control device. 130

8. In a central lubricating system having a lubricant supply, a lubricant pipe system and a vacuum pump for forcing lubricant through the pipe system, a combined pump 5 control and lubricant pressure relief device, a lubricant conduit leading through said control device, a vacuum conduit leading through said control device and a slide valve element operable to open one of said conduits while 10 closing the other of said conduits. 9. In a central lubricating system having a lubricant supply, a lubricant pipe system and a vacuum pump for forcing lubricant through the pipe system, a combined pump 15 control and lubricant pressure relief device, a lubricant conduit leading through said control device, a vacuum conduit leading through said control device and a combined hand operable and lubricant pressure operable slide valve element operable by hand 20 in one direction to open the vacuum conduit and close the lubricant conduit, and by lubricant pressure in the opposite direction to close the vacuum conduit and open the lubricant conduit. 10. In a central lubricating system having a lubricant supply, a plurality of points to be lubricated and a pipe system connecting said points with the lubricant supply, a suction-operated pump inserted in the pipe system 30 for forcing the lubricant to the points to be lubricated, said pump having a piston operable in opposite directions by alternately admitting atmospheric pressure to opposite 35 sides of said piston while admitting suction at the side opposite the side at which the atmosphere is admitted, means providing a plurality of ports and a disklike valve adapted to be operated by the movement of said piston to control the admission of atmosphere 40 and suction to said piston. 11. In a central lubricating system having a lubricant supply, a plurality of points to be lubricated and a pipe system connecting 45 said points with the lubricant supply, a suction operated pump inserted in the pipe system for forcing the lubricant to the points to be lubricated, said pump having a piston operable in opposite directions by alternately 50 admitting atmospheric pressure to opposite sides of said piston while admitting suction at the side opposite the side at which the atmosphere is admitted, means providing a plurality of ports and a disklike valve communicating with one of said ports at all times 55 and adapted to be moved by movement of said piston to alternately communicate with and uncover each of the other of said ports. 12. In a central lubricating system having 60 a lubricant supply, a plurality of points to be lubricated and a pipe system connecting said points with the lubricant supply, a suction-operated pump inserted in the pipe system for forcing the lubricant to the points 65 to be lubricated, said pump having a piston 70 operable in opposite directions by alternately admitting atmospheric pressure to opposite sides of said piston while admitting suction at the side opposite the side at which the atmosphere is admitted, means providing a plurality of ports, a disk-like valve for controlling the admission of the atmospheric pressure and the suction for operation of said piston and a lost motion connection between the valve and said piston for moving said valve from one set of ports to the other. 75 13. In a central lubricating system, the combination of a source of lubricant, a lubricant pipe system, a vacuum operated pump, a conduit for connecting said pump to a reduced pressure source of power, a manually operable valve in said conduit, and means responsive to the lubricant pressure in said pipe for closing said valve. 80 14. In a central lubricating system, the combination of a source of lubricant, a lubricant pipe system, a power operated pump for forcing lubricant from said source to said pipe system, means manually operable to control the supply of power to said pump, means operable upon a predetermined pressure of lubricant in said pipe system automatically to actuate said control means to cut off the supply of power to said pump, and adjustable means for predetermining the lubricant pressure necessary to operate said last-named means. 85 90 95 In testimony whereof, I have signed my name to this specification. HOWARD J. MURPHY. 100 105 110 115 120 125 130
